[57] CLAIM

The ornamental design for the roller meat tenderizer, as shown and described.

DESCRIPTION

FIG. 1 is a front elevational view of the roller meat tenderizer showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is an enlarged detail view of the area indicated by the broken line circle in FIG. 6;

FIG. 8 is a cross-sectional view thereof taken along line 8—8 of FIG. 1; and,

FIG. 9 is a cross-sectional view thereof taken along line 9—9 of FIG. 1.
